FIG. 1

Inventor

Julius Venne

By *Geo. P. Kimmel*
Attorney

UNITED STATES PATENT OFFICE.

JULIUS VENNE, OF DEER RIVER, MINNESOTA.

CAR-STAKE.

1,373,277.

Specification of Letters Patent. Patented Mar. 29, 1921.

Application filed July 13, 1920. Serial No. 395,837.

To all whom it may concern:

Be it known that I, JULIUS VENNE, a citizen of the United States, residing at Deer River, in the county of Itasca and State of

5 Minnesota, have invented certain new and useful Improvements in Car-Stakes, of which the following is a specification.

This invention relates to improvements in car stakes, and more particularly to the connections between the upper terminals of the stakes, whereby the latter are maintained in position on the opposite sides of the car.

The invention has for its principal object to provide a novel type of coupling between 15 the upper terminal of the stake and the connecting chain whereby the latter is automatically detached from the stake upon the release and subsequent turning movement of the latter incident to the pressure exerted 20 thereon by the carload of logs.

With this and other objects in view, the invention consists in certain novel features of construction as hereinafter shown and described and then specifically pointed out 25 in the claims, and in the drawings illustrative of the preferred embodiment of the invention.

In the accompanying drawings:

Figure 1 represents a perspective view of 30 the upper terminal of the stake illustrating the fastening device for the connecting chain in detail.

Fig. 2 represents a fragmental plan view of a car illustrating the manner of connecting 35 the stakes at the opposite sides thereof, and,

Fig. 3 represents a side elevation of the stake.

Referring to the drawing in detail, where- 40 in similar reference numerals designate corresponding parts throughout the several views, the numeral 5 indicates the body of the stake which may be of any approved type being preferably squared at its lower portion 5^a and is mounted in a releasable type of pocket 6. A horizontal flat plate 6^a secured in any suitable manner to the car body 12 is adapted to support the squared base of the stake when in its upright position as shown in Fig. 3. Although the specific form of the pocket does not form part 50 of the present invention an approved type have been illustrated in detail in the accompanying drawing which includes a hinged keeper plate 7 which is maintained in operative position to support the stake vertically

by a removable pin 8, the latter being ar- 60 ranged for convenient removal to permit of displacement of the stake when it is desired to unload the logs.

The lower terminal of the stake is connected with a relatively short chain section 9 having the end link 10 thereof provided with an enlarged terminal portion 10^a permitting the chain 11 to be freely moved 65 therethrough. The chain 11 is fastened to the side of the car body 12 adjacent the stake holder 6 and is engaged with the relatively narrow portion of the link 10 of the chain 9 to support the stake subsequent to 70 its release and thereby prevent loss thereof.

As usual, the stakes are arranged in pairs upon the car, the stakes of each pair being arranged on opposite sides of the car and being connected by a chain connection 13.

Adjacent the upper end of each stake an eye bolt 14 is passed therethrough and is provided at the looped terminal thereof with a permanently attached ring 15. The elongated and curved shank 16 of a hook 17 is secured to each end of the adjustable connecting chain 13 of the pair of stakes and the shape of said shank is such as to permit it to partially embrace the upper terminal of the stake. When the stake is 85 properly set up in the holder 6, the shank 16 lies in engagement with one side face and the outer face of the stake and the hook 17 thereof engages in the link 15 thereby establishing a strong connection between 90 the chain and stake and preventing the latter from moving outwardly under the weight of the logs on the car. As clearly shown in Fig. 1, the beak of the hook 17 is directed outwardly in a horizontal plane so that as the 95 stake turns, subsequent to being released, the hook is automatically disengaged from the link 15 thereby releasing the upper terminal of the stake and permitting the latter to fall down beside the car. The chain connections 9 and 11 between the lower terminal of the stake and the car prevent loss of the stake subsequent to its release.

In use, the stakes of the car are properly positioned in the holders 6 and subsequent 105 to partially filling the car with logs, the terminals of the stakes are connected by the chains 13, the hooks 17 engaging in the links 15. Owing to the manner in which the shanks 16 of the hooks curve and embrace 110 the stakes, a reliable connection between the hooks and links is established. Subsequent

to applying the connecting chains, additional logs may be placed upon the car. The stakes are released in the usual manner by withdrawing the pins 8 from the holders 6 and as the stakes fall downwardly by gravity they are partially turned owing to their connection with the chains 13 thereby automatically withdrawing the terminals of the hooks 17 from the rings 15. It will of course be understood that the squared base of the stakes will be prevented from turning before the keeper plate 7 is released. By this improvement, it is evident that the stakes are completely disconnected at their upper terminals from the connecting chains and offer no obstruction whatever to the logs as the latter are rolled off of the car, while the weight of the logs is utilized to positively effect the turning movement of the stakes, by which action the automatic disconnection of the chains from the stakes is effected. Furthermore, due to the fact that it is unnecessary to manipulate the connecting chains 13 during manual release of the stake, it is evident that the improvement adds to the safety of devices of this character.

The preferred embodiment of the invention is disclosed in the drawings and set forth in the specification, but it will be understood that any modifications within the scope of the claims may be made in the construction without departing from the principle of the invention or sacrificing any of its advantages.

35 5. What is claimed is:

1. In a device of the class described, a car stake adapted for engagement in a holder, a connection for the upper terminal of the stake, and releasable, flexible attaching means for the connection constructed and arranged to effect turning movement about an axis longitudinal with respect to the stake by the pressure of logs thereon and to be disengaged from the stake upon turning 45 of the latter.

2. In a device of the character described, a stake, a removable connection for the upper terminal thereof, and releasable, flexible attaching means for the connection ar-

ranged to utilize the pressure of logs against the stake in effecting turning movement about an axis longitudinal with respect to the latter and operable, upon turning movement of the stake to release the latter.

3. In a device of the character described, a releasable stake holder, a stake arranged therein, a support for the holder, a flexible connection between the stake and support, a semi-circular connection for the upper terminal of the stake, and attaching means for said connection for maintaining the stake in operative position and operable, upon turning movement about an axis longitudinal with respect to the latter, to release the stake.

4. In a device of the character described, a stake, a removable connection for the upper terminal thereof, a releasable attaching element carried by the connection adapted to partially embrace the stake to effect turning movement of the latter incident to pressure exerted thereon by logs, and means carried by the stake for cooperating with the attaching element and operable, upon turning movement about an axis longitudinal with respect to the stake, to release the latter.

5. In a device of the character described, a car stake, a removable connection for the upper terminal thereof, a hook having a curved shank connected with the connection and adapted to partially embrace the stake when the latter is arranged in operative position, and means carried by the stake cooperating with the hook constructed and arranged to disengage from the hook by a turning movement about an axis longitudinal with respect to the stake.

6. In a device of the character described, a car stake, a ring loosely connected therewith, a connection for the upper terminal of the stake, and a hook carried by the connection adapted to partially embrace the terminal of the stake when the latter is operationally positioned and having the beak disposed to engage in the ring.

In testimony whereof, I affix my signature hereto.

JULIUS VENNE.
